UNITED STATES PATENT OFFICE.

FRANK FUREDY, OF MONTCLAIR, AND CHARLES SCHROTH AND WILLIAM FAVINI, OF BLOOMFIELD, NEW JERSEY, ASSIGNEES, BY MESNE ASSIGNMENTS, TO BUSHWICK NATIONAL BANK.

WRITING IMPLEMENT.

Application filed July 28, 1925, Serial No. 46,535. Renewed June 16, 1928.

Our invention relates to writing implements, and particularly to pencils in which a plurality of leads or similar marking elements are mounted for quick, selective movement to and from active position.

The general object is to provide such a pencil of very simple and economical construction without sacrificing any essential structural or operative features.

10 A more particular object is to provide such a pencil without the necessity for employing cranked lead carriers or carriers having offset lead grips, which must be partly rotated as they are moved to and 15 from writing position. For this purpose the invention includes substantially straight lead carriers or stems and co-operating supporting and guiding means so constructed and arranged that the stems move very close together and near the longitudinal axis of the pencil, and the lead carried by either stem 20 may therefore be projected in writing position with very slight, practically unnoticeable, and unobjectionable deflection of the 25 stem or the lead grip proper, or of the lead.

The invention includes structures and arrangements of parts for carrying out the above and other objects, and also includes a novel and economical form of lead carrier 30 impelling helix and carrier-guide arrangement as fully described hereafter.

The characteristics and advantages of the invention are further sufficiently explained in connection with the following detail description of the accompanying drawing, which shows certain representative embodiments of the invention. After considering these exemplifications, persons skilled in the art will understand that many variations 40 may be made within the principles of the invention, and we contemplate the employment of any structures that are properly within the scope of the appended claims.

Fig. 1 is a longitudinal section of a pencil 45 embodying the invention in one form.

Fig. 2 is a perspective view of certain of the separate parts.

Fig. 3 is a section at 3—3, Fig. 1, enlarged.

Fig. 4 is a perspective view of the upper 50 portion of the case, sectioned to clearly show the spare lead holder or magazine therein.

Fig. 5 is a section at 5—5, Fig. 1.

Fig. 6 is a detail view, enlarged, of the upper thimble.

55 The main body or tubular case 1 may be

of almost any material, including metal, but since it is usually preferred to have the wall of this case of substantial thickness, it is preferably made of a fairly light non-metallic moldable substance or composition. The 60 hollow center of the case includes the main bore 2 of moderate diameter, the lower-end enlarged counter bore 3 and the upper enlarged counter bore 4. A lower thimble 5 is located in the counter bore 3 with a force 65 fit. To aid in securing the thimble against displacement and especially against rotation, its cylindrical periphery is provided with corrugations or longitudinal serrations 6 70 adjacent flange 7. When the main cylindrical part of the thimble is inserted in the counter bore 3, the serrations cut their way into the material of the lower end of the counter bore until flange 7 seats against the lower end of the case. The thimble is then 75 effectively locked against displacement or rotation. The outward portion of the thimble, projecting beyond flange 7, has an external screw thread 8 co-operating with an internal thread 9 on the tip 10, which is thus 80 detachably connected to the case. Usually the tip is of tapered, conical or conoidal form, and has at its end the lead bore 11 which is, of course, in the longitudinal axis 85 of the pencil.

A spare lead holder or magazine 15 is located with a force fit in the upper counter bore 4. The magazine may be of almost any material including metal or any suitable moldable composition. It is provided with 90 longitudinal channels 16, each large enough to receive a single lead of standard size, and when located in the case each of these channels in conjunction with the case wall forms a separate lead chamber accessible at the 95 upper end of the case for insertion or removal of the spare leads. Desirably the magazine has a cut-away or flattened face 17 to accommodate inward portions of fastening devices 18, which secure a spring pocket 100 clip 19 to the outside of the case.

An upper thimble 20 is located with a bearing fit in the upper end of the cylindrical bore 21 of magazine 15. The thimble consists of upper and lower cylindrical 105 portions 22 and 23 connected by a central transverse web 24. The external diameter of the lower cylindrical portion 23 is slightly smaller than that of the upper portion 22, producing at the intersection of these 110

portions a shallow shoulder 25 which rests on the upper end of the magazine.

A head 30, a portion of which is accessible for finger manipulation to actuate the active leads, is located with a friction fit on upper cylindrical portion 22. The fit is tight enough to prevent accidental displacement, but not tight enough to prevent ready removal to give access to the spare leads.

10 To prevent relative rotation of the head and thimble, the upper cylindrical wall 22 of the latter is provided with a longitudinal slot 31 to receive a lug 32 pressed in from the integral metal of the head. The head 15 includes an upper cylindrical portion 34 fitting around thimble portion 22, and an extension 35 to receive a rubber eraser 36. A protecting cap 37 encloses the eraser and has an internal screw thread engaging an external thread on cylindrical head portion 34 to permit easy removal and replacement of the cap. The head also includes a thick flange 40 having a knurled periphery 41 exposed for convenient finger manipulation.

25 A lead carrier guide 45 passes through a circular hole 46 and through the central portion of an aperture 47 in the lower end of the lower thimble 5. This guide or lead carrier support is of substantially H-section and may be produced from a round rod (or of course, it may be molded or otherwise produced) by milling therein two opposite longitudinal channels 50, 51, leaving a central web 52 which is as thin as possible, consistent with necessary strength. Intermediate the channels the guide surface consists of two part-cylindrical portions 53. The lower end of the guide is tapered off as at 54 and this lower end portion projects 40 below the lower end of the lower thimble 5 a substantial distance, within the hollow tip 10. The lower portion of the guide is secured irrevolubly in the thimble in any convenient way, for example, by soldering 45 or by swaging or forcing together adjacent portions of the guide and thimble. The upper end of the guide projects above the central web 24 of the upper thimble, and the thimble and connected parts are prevented 50 from upward displacement by a ring or collar 56 placed on the upper end of the guide and soldered or secured in any other convenient way. Just below the collar the circular hole in the thimble web has a bearing fit about the part-cylindrical guide surfaces 53.

55 A lead carrying stem is located in each of the guide channels. Thus a long stem 60 is located in channel 50, and a short stem 61 in channel 51. The stems are of such diameter that they are contained entirely within the channels and without any disadvantageous results the stems may be so small that they have a very loose fit in the 60 channels.

The carrier stems are of any suitably strong and resilient metal. Piano wire is a desirable material since even in small diameters it is very strong and has substantial stiffness although it is at the same time 70 resilient and easily bent to the small degree necessary to permit the lead which is being projected to writing position to be deflected to the center line of the case, as later explained.

75 Near the upper end each stem has an impeller follower, identified as 62 for the follower on stem 60, and 63 for the one on stem 61. These followers may be shaped up from metal blocks, the bodies 64 being 80 drilled longitudinally for reception of the stems. In some cases the upper end of the stem may project above the follower body as indicated for stem 61 in the drawing, but this is not necessary in all cases. Lugs 65 85 project from the outward face of each impeller body and the inward faces of the lugs are formed substantially parallel and angularly to fit the impeller helix. The follower bodies 64 are of cross section approximate to that of the channels 50 and 51, or in other words, have a fairly close sliding fit in the channels.

90 At the lower end each stem 60-61 has a suitable lead grip 70-71 respectively. 95 These grips may be slidable on the stems for purposes of lead ejection, but the ejector feature is not a part of the present invention and details of the grips are therefore not described.

100 The aperture 47 in the lower thimble 5 has opposite enlargements 75 to provide ample clearance for the passage of the lead grips.

105 A helical impeller is arranged for rotation about the stem guide. In some cases this impeller may be of substantially continuous form, but for greater manufacturing convenience it consists of an upper section 80 corresponding to lead carrying stem 60, and a lower section 81 corresponding to stem 61. These sections are made of wire of substantial thickness and stiffness. Each impeller section consists of two parts, a lower part 83 of steep pitch to give rapid lead movement and an upper part 84 of fine pitch to give slow lead movement. The two helices have opposite leads, that is, either one may have a right-hand lead corresponding to a right-hand screw, and the other has a left-hand lead or pitch.

110 The lower end of the lower helix 81 extends within the lower thimble 5 and is revoluble therein and about the guide 45. The upper end of the lower helix and the lower end of the upper helix are located in and fixed to a sleeve 86 which has a rotary bearing fit in the main case bore 2. The helices are secured to the sleeve in any convenient way, for example by soldering. The sleeve 86 may be dispensed with in some cases, but 115 120 125 130

is conveniently employed when the impellers are made in two sections for convenient connection of the sections together, and also to provide a central bearing and stiffen the connected impellers against lateral deflection and also by engagement of the impellers with the guide unit 45 to position the latter at an intermediate point in its length. The upper end of the upper helix 80 is located in the hollow lower portion 23 of the upper thimble 20, and is secured in any convenient way, for example, by solder at the point 88 to connect a peripheral portion of the impeller helix with the adjacent edge of the thimble member 23.

With the parts in the position shown in Fig. 1, to withdraw the lead which is in projected position and to project the inactive lead, the finger flange or knob 30 is turned counter-clockwise. The upper helix 80, located between lugs 65 of the follower 62, then moves the follower and the connected lead carrier stem 60 with its lead grip 70 and lead, down, while the lower helix 81 in engagement between the lugs 65 of the follower 64 moves the other lead stem 61, grip lead and grip, upward. The lead stems, grips and leads move very close together being separated only by the thickness of the central guide web 52 or in other words, the carriers and leads are always very close to the axis of the pencil. The movement of the inside lead toward projected position is at first slow, because the follower lugs are in engagement with the fine pitch portion of the helix while retraction of the projected lead is relatively rapid, because its follower lugs are in engagement with the steep pitch portion of the helix 81. When the lead held by grip 70 approaches the tip opening or in other words, is nearly in projected position, its movement will be rapid because the corresponding follower lugs then engage the steep pitch portion of their helix 80, and the movement of the other lead which is now being retracted becomes relatively slow by engagement of its follower lugs with the fine pitch portion of helix 81. From one point of view therefore, the fine pitch portions of the helices are provided so that the movement of the indrawn or inactive lead, which is necessary to permit sufficient movement of the projected or active lead, is relatively small and therefore only a small part of the total length of the pencil is necessary for the purpose of providing this inactive lead movement. As the inside lead carried by grip 70 approaches the tip opening 11, its lower end strikes the inner conical wall of the tip, and is deflected slightly so that the lead passes freely through the tip hole without any considerable angularity or any considerable deflection of the lead stem, and so far as the user can ob-

serve, the lead projects substantially straight from the pencil tip, the same as if it and its carrier were actually in the exact longitudinal axis of the pencil. The carrier stems bend slightly to permit necessary deflection of the leads and carriers to the case axis. This bending is indicated only approximately in Fig. 1, where there is a slight bend in the carrier stem of the projected lead at about the point where the stem is joined to the lead grip 71. Actually the slight curvature of the stem will be in a long arc which it is impracticable to represent in the drawing, and this slight degree of bending imposes no appreciable or objectionable strain upon the carrier stem or any other parts. The tip hole 11 is made to have a fairly snug sliding fit on a lead of standard size, and when so made there is no appreciable lateral play; the nature of the impeller helices and followers and other related parts, is also such that there is absolutely or practically no end play of the leads and when properly projected and adjusted, the lead is held firm and true, substantially as in a fixed-lead pencil.

Reverse motion of the finger knob 30 moves the lead carriers and leads in opposite directions, as will be obvious without further explanation.

The shape and arrangement of the upper and lower thimbles and especially as to the latter, the arrangement of the inward tubular portion 23, accommodates the lower and upper ends of the respective helices, and also permits free motion of the followers with their lugs to the lower and upper ends of the respective helices at which time the follower 64 is substantially at the bottom of thimble 5 and the other follower 62, is at the upper end of thimble portion 23 or against the transverse wall 24 thereof.

The confronting faces of the follower lugs are somewhat rounded off, in a way which it is difficult to show in the drawing, to cooperate with the different pitch portions of the helices, or in other words, so that the lugs have a snug but easy sliding fit on both portions of the helix, without any perceptible lost motion.

Only two lead holders and leads are employed in the present specific construction, but many of the features disclosed are adaptable to pencils having three or more lead carriers, and also certain features are adaptable to a pencil having only one movable lead carrier and lead.

While in a two-lead pencil one lead may be projected while the other is retracted and really idle or inactive, or both leads may be in retracted position at the same time to prevent injury to a projecting lead point when not in use, the two leads are really mounted or arranged in active positions since they are available immediately for use

by merely turning the controlling knob. In certain claims therefore, reference is made to two or a plurality of active leads or other similar language is used, and to distinguish between a lead positioned for writing and one which is withdrawn and idle, reference is made to projected and retracted leads or lead positions.

We claim:

1. A multi-lead pencil comprising a case having a tip provided with a lead aperture at the case axis, a central guide, a plurality of lead carriers located close together and close to the longitudinal axis of the pencil and in directive engagement with the guide, and means for moving the carriers to and fro, the tip and lead aperture co-operating with leads mounted in the carriers to guide one lead to projected, substantially axial position by slight deflection of its carrier, while the other carrier and its lead are being withdrawn within the case.

2. A multi-lead pencil comprising a case having a tip provided with a lead aperture at the case axis, a central guide, a plurality of lead carriers located close together and close to the longitudinal axis of the pencil and in directive engagement with the guide, and means for moving two of the carriers simultaneously to and fro in opposite directions, the tip and lead aperture co-operating with leads mounted in the carriers to guide one lead to projected, substantially axial position by slight deflection of its carrier, while the other carrier and its lead are being withdrawn within the case.

3. A multi-lead pencil comprising a case, a tip with a substantially conical interior leading to a lead opening at the point end, a fixed guide extending longitudinally within the case substantially at the case axis and terminating at a point substantially upward from the lead opening, a plurality of lead carrier stems arranged parallel and close together and close to the pencil axis and in directive engagement with the guide, and means for moving the stems to and fro, the tip and lead opening co-operating with one of the leads as the respective carrier is moved outward to locate the projected lead in substantially axial position by slight deflection of the carrier while the other carrier and its lead are being withdrawn within the casing.

4. A multi-lead pencil comprising a case, a tip with a substantially conical interior leading to a lead opening at the point end, a fixed guide extending longitudinally within the case substantially at the case axis and terminating at a point substantially upward from the lead opening, a plurality of lead carrier stems arranged parallel and close together and close to the pencil axis and in directive engagement with the guide, and means for simultaneously moving one carrier inward and the other outward, and vice

versa, the tip and lead opening co-operating with one of the leads as the respective carrier is moved outward to locate the projected lead in substantially axial position by slight deflection of the carrier while the other carrier and its lead are being withdrawn within the casing.

5. A multi-lead pencil comprising a case, a central guide, a plurality of lead carriers located parallel and close together and close to the longitudinal axis of the pencil and in directive engagement with the guide, said carriers also being arranged for projection of their respective leads selectively at the same end of the case, and a helical impeller mounted for rotation about the guide and in engagement with the carriers.

6. A multi-lead pencil comprising a case, a central guide, a plurality of lead carriers located parallel and close together and close to the longitudinal axis of the pencil and in directive engagement with the guide, said carriers also being arranged for projection of their respective leads selectively at the same end of the case, and impelling means comprising two connected helical sections of opposite pitch-lead arranged for rotation about the guide, and in engagement with the carriers.

7. A multi-lead pencil comprising a case, a central guide, a plurality of lead carriers located parallel and close together and close to the longitudinal axis of the pencil and in directive engagement with the guide, said carriers also being arranged for projection of their respective leads selectively at the same end of the case, and impelling means comprising connected upper and lower helical sections of opposite pitch-lead arranged for rotation about the guide, one of the carriers having a follower engaging the upper impeller section and the other carrier having a follower engaging the lower impeller section.

8. A multi-lead pencil comprising a case, a tip with a substantially conical interior leading to a lead opening at the point end, a fixed guide extending longitudinally within the case substantially at the case axis and terminating at a point substantially upward from the lead opening, a plurality of lead carrier stems arranged parallel and close together and close to the pencil axis and in directive engagement with the guide, and a helical impeller mounted for rotation about the guide and in driving engagement with the carrier stems.

9. A multi-lead pencil comprising a case, a tip with a substantially conical interior leading to a lead opening at the point end, a fixed guide extending longitudinally within the case substantially at the case axis and terminating at a point substantially upward from the lead opening, a plurality of lead carrier stems arranged parallel and close to

gether and close to the pencil axis and in directive engagement with the guide, and impelling means comprising two connected helical sections of opposite pitch-lead arranged for rotation about the guide.

10. A multi-lead pencil comprising a case, a tip with a substantially conical interior leading to a lead opening at the point end, a fixed guide extending longitudinally with-
10 in the case substantially at the case axis and terminating at a point substantially upward from the lead opening, a plurality of lead carrier stems arranged parallel and close together and close to the pencil axis and in
15 directive engagement with the guide, and im-
pelling means comprising two connected helical sections of opposite pitch-lead ar-
ranged for rotation about the guide, one of
20 the carrier stems being relatively long and
20 having a follower engaging the upper im-
peller section and the other carrier stem
being relatively short and having a fol-
lower engaging the lower impeller section.

11. A pencil comprising a case, a substan-
25 tially central guide therein having channels
separated by a thin web, lead carriers ar-
ranged for longitudinal movement in the
channels, and an impeller in the form of a
30 metal rod bent in helical form and located
for rotation about the guide, the carriers
having means engaging the impeller helix
for reciprocation of the carriers by rotation
of the helix.

12. A multi-lead pencil comprising a
35 tubular case, a tip having a substantially
conical interior leading to the lead aper-
ture at the tip end, a central fixed guide
having longitudinal channels, lead carrier
40 stems mounted for reciprocation in the
channels and each having a grip for an
active lead, an impeller helix having two
connected sections of opposite lead arranged
45 for rotation about the guide, and externally
accessible means for rotating the helix
to move one lead to projected position while
the other is retracted, and vice versa.

13. A multi-lead pencil comprising a
50 tubular case, a tip having a substantially
conical interior leading to the lead aper-
ture at the tip end, a central fixed guide
having longitudinal channels, lead carrier
55 stems mounted for reciprocation in the
channels and each having a grip for an
active lead, an impeller helix having two
connected sections of opposite lead arranged
60 for rotation about the guide, externally ac-
cessible means for rotating the helix to move
one lead to projected position while
the other is retracted, and vice versa, and
65 a fitting located near the lower end of the
case in which the lower portion of the guide
is fixed.

14. A multi-lead pencil comprising a
70 tubular case, a tip having a substantially
conical interior leading to the lead aper-

ture at the tip end, a central fixed guide
having longitudinal channels, lead carrier
70 stems mounted for reciprocation in the
channels and each having a grip for an
active lead, an impeller helix having two
connected sections of opposite lead arranged
75 for rotation about the guide, externally ac-
cessible means for rotating the helix to move
one lead to projected position while the other
is retracted, and vice versa, and a fitting
80 located near the lower end of the case in
which the lower portion of the guide is
fixed, the fitting being of tubular form to
accommodate a lower portion of the impeller
helix.

15. A multi-lead pencil comprising a
tubular case, a tip having a substantially
conical interior leading to the lead aper-
ture at the tip end, a central fixed guide
85 having longitudinal channels, lead carrier
stems mounted for reciprocation in the
channels and each having a grip for an
active lead, an impeller helix having two
connected sections of opposite lead arranged
90 for rotation about the guide, externally ac-
cessible means for rotating the helix to move
one lead to projected position while the
other is retracted, and vice versa, a fitting
95 rotatably mounted near the upper end of the
case, the upper end of the impeller helix
being secured to said fitting, and an exter-
nally accessible member connected to the fit-
ting for rotating the latter and the impeller
to move the carriers to and fro.

16. A multi-lead pencil comprising a
100 tubular case, a tip having a substantially
conical interior leading to the lead aper-
ture at the tip end, a central fixed guide
having longitudinal channels, lead carrier
105 stems mounted for reciprocation in the
channels and each having a grip for an
active lead, an impeller helix having two
connected sections of opposite lead arranged
110 for rotation about the guide, externally ac-
cessible means for rotating the helix to move
one lead to projected position while the
other is retracted, and vice versa, a fitting
115 rotatably mounted near the upper end of the
case, the upper end of the impeller helix
being secured to said fitting, and an exter-
nally accessible member connected to the fit-
ting for rotating the latter and the impeller
120 to move the carriers to and fro, said fitting
being of tubular form to accommodate an
upper portion of the impeller helix.

17. A multi-lead pencil comprising a
tubular case, a tip having a substantially
conical interior leading to the lead aper-
ture at the tip end, a central fixed guide
125 having a grip for an active lead, an impeller
helix having two connected sections of oppo-
site lead arranged for rotation about the
guide, externally accessible means for rotat-
ing the helix to move one lead to projected
130

position while the other is retracted, and vice versa, and a spare lead magazine located in an upper counter-bore of the case, the magazine having longitudinal peripheral channels forming spare-lead pockets in conjunction with the adjacent case wall.

18. A multi-lead pencil comprising a tubular case, a tip having a substantially conical interior leading to the lead aperture at the tip end, a central fixed guide for reciprocation in the channels and each having a grip for an active lead, an impeller helix having two connected sections of opposite lead arranged for rotation about the guide, externally accessible means for rotating the helix to move one lead to projected position while the other is retracted, and vice versa, a spare lead magazine located in an upper counter-bore of the case, the magazine having longitudinal peripheral channels forming spare-lead pockets in conjunction with the adjacent case wall, and a fitting rotatably mounted in an upper part of the magazine and connected to the impeller helix to rotate the same.

19. Operating mechanism for a multi-lead pencil comprising a substantially cylindrical, longitudinally channeled guide, a wire impeller helix having a close rotatable fit about the guide, lead-carrier stems located in

the channels, and follower lugs projecting from the stems and engaging opposite sides of the impeller helix.

20. A multi-lead pencil comprising a case having a lead aperture at one end, a revolvable operating knob at the other end of the case, lead carrier stems in the case, each stem having means for supporting a lead, and the stems and other parts being adapted for the selective projection of one lead at a time through said lead aperture, a central longitudinal guide having means for locating the carrier stems and directing them for straight line movement in parallel relation near the axis of the case, and an impeller mounted for rotation about the guide, the impeller having helical formations of opposite lead at different portions of its length, one of said helical formations co-operating with one of the carrier stems and the other formation co-operating with the other carrier stem to move the stems simultaneously in opposite directions when the impeller is rotated.

Signed at Belleville, in the county of Essex and State of New Jersey, this 23 day of July A. D. 1925.
